(57) **CLAIM**

I claim the ornamental design of a solar power generator, substantially as shown and described.

DESCRIPTION

FIG. 1 is a front perspective view of a solar power generator in accordance with the present invention;

FIG. 2 is a top view of the solar power generator in FIG. 1;

FIG. 3 is a bottom view thereof;

FIG. 4 is a left side view thereof;

FIG. 5 is a right side view thereof;

FIG. 6 is a front view thereof;

FIG. 7 is a back view thereof;

FIG. 8 is a top perspective view of the solar power generator in an open configuration;

FIG. 9 is a top view of the solar power generator in FIG. 8;

FIG. 10 is a bottom view thereof;

FIG. 11 is a left side view thereof;

FIG. 12 is a right side view thereof;

FIG. 13 is a front view thereof; and,

FIG. 14 is a back view thereof.

The broken lines illustrate the portions of the solar power generator that form no part of the claimed design.
